UNITED STATES PATENT OFFICE

CHARLES L'ENFANT, OF NEW YORK, N. Y.

METHOD OF REENFORCING THE WALLS OF BILL FOLDS, CARD CASES, AND SIMILAR ARTICLES.

Application filed June 4, 1929. Serial No. 368,213.

This invention relates to a method of reenforcing the relatively foldable flexibly connected walls of bill-folds, card cases and similar articles.

It is the primary object and purpose of my present invention to provide a method whereby the application of the reenforcing material to one side of the fabric walls may be greatly expedited whereby the quantity 10 production of such articles at very low manufacturing cost will be realized.

My present method has for a more particular object to attain the rapid application of the reenforcing material, to selected parts 15 of the fabric sheet, the portions of the sheet immediately contiguous to the folds thereof being unreenforced.

With the above and other objects in view, the invention consists in the improved 20 method, as will be hereinafter more fully described in detail, illustrated in the accompanying drawings, and subsequently incorporated in the subjoined claims.

In the drawings, wherein I have illustrated 25 several applications of my new method and the production of different articles, and in which similar reference characters designate corresponding parts throughout the several views,—

30 Figure 1 is a perspective view of a combined bill and card case, in the manufacture of which the present method may be advantageously used;

35 Fig. 2 is a plan view, illustrating the manner of application of the reenforcing material to one side of a fabric sheet adapted to be secured to the body walls of the case and foldable therewith;

40 Fig. 3 is a similar view illustrating the completed reenforcing foldable inner wall of the case;

Fig. 4 is an enlarged detail section taken on the line 4—4 of Fig. 3;

45 Fig. 5 is a plan view showing one of the inner wall sections of the case forming a bill receiving pocket;

Fig. 6 is a plan view showing the reenforced fabric walls illustrated in Figs. 3 and 5 assembled;

Fig. 7 is an end view showing the arrangement of the inner fabric parts of the case illustrated in Figs. 3 and 5 with respect to the outer body wall of the case before the several parts are secured together in finally 65 assembled relation;

Fig. 8 is a horizontal sectional view taken on the line 8—8 of Fig. 1;

Fig. 9 is a fragmentary longitudinal sectional view taken on the line 9—9 of Fig. 1, 60 and

Figs. 10 and 11 are plan views illustrating an application of my new method in the production of a billfold.

Referring in detail to the drawings, the bill and card case illustrated in Figs. 1 to 9 thereof, includes opposite side walls 5 of equal area and of suitable length and width which are preferably formed from a single sheet of leather indicated at 6 folded upon itself as at 7, said leather sheet having a suitable reenforcing material such as silk secured to the inner face thereof as shown at 8.

With one of the side walls 5 of the case, 75 an inner pocket forming wall 9 is associated and extends the entire length of the outer side wall 5. As indicated in Fig. 5 of the drawings, this wall 9 which is also of silk or other suitable flexible material has a reenforcing sheet adhesively secured on one side thereof, the edge of said reenforcing sheet indicated at 10 being turned over and secured upon the opposite side face of the fabric wall.

80 A second bill receiving pocket is also provided in conjunction with the other outer side wall 5 of the case, while additional card receiving pockets are provided on the wall 9. These additional pockets are produced from a single sheet of silk or other flexible material shown at 11. To one side of this sheet of fabric material and covering the entire area thereof, a reenforcing sheet 12 of fabric, paper or other material is adhesively secured. 90

95 Opposite side edges of the material 11 are adapted to be turned inwardly upon and secured to the reenforcing sheet 12; and intermediate of said edges, the fabric sheet 11 is adapted to be folded to provide a hinge fold 100

therein at 13 corresponding to the fold 7 connecting the opposite outer side walls 5 of the case. Therefore, after the sheet of reenforcing material 12 has been applied, 5 narrow strips of this material indicated at 14 in Fig. 2 of the drawings, at the opposite edges 11 thereof, and at the fold 13 are removed. The reenforcing sheet 12 is relatively light, and these strips may be readily 10 torn out and separated from the fabric sheet 11. The edges of the sheet 11 are then turned inwardly and adhesively secured on the re-enforcing sheet 12 as shown at 15 in Fig. 3.

Having thus prepared the several parts, 15 the wall 9 is arranged in opposed relation to the relatively narrow reenforced section of the wall 11 at one side of the hinge fold 13 and is secured thereto by the spaced lines of stitching shown at 16, it being noted from 20 reference to Fig. 6 that the wall 9 is of greater width than the part of the reenforced fabric sheet 11 to which it is secured. The connected parts 9 and 11 are then inverted from the position shown in Fig. 6 and ar- 25 ranged in superposed relation upon the re-enforced side of the outer flexible leather sheet 6 which forms the opposite side walls 5 of the case. The opposite longitudinal edges of the leather sheet 6 are then turned in- 30 wardly and then secured upon the reenforcing sheet 8 and the end edges of said leather sheet forming each of the outer side walls of the case is also turned inwardly and se- 35 cured together with the end edges of the parts 9 and 11 by the stitching indicated at 17. The opposite end edges of these parts and the corresponding end edges of the outer side walls 5 of the case are permanently secured together by the line of stitching 18. 40 Thus, it will be understood that the latter end of the case is permanently closed. From reference to Fig. 1, it will therefore, be seen that the folded reenforced fabric sheet 11 provides a bill receiving pocket extending 45 the full length of one side wall of the case and also the inner walls of additional card receiving pockets on the separate inner wall 9 of the bill receiving pocket which is carried by the opposite outer side wall of the case. 50 By means of the method above described, it will be observed that each of the pocket forming walls is strongly reenforced, and the reenforcing material may be easily and quickly applied to the walls of the sheet 11 while 55 that part of the fabric sheet which forms the hinge fold 13, is unreenforced, so that it will occupy but relatively little space within the body of the case at the fold line 7 thereof. As the opposite side walls of the case at one 60 of their ends are unconnected, bills, papers, or memoranda may be conveniently and safely carried in the space between the walls of the card receiving pockets and the inner wall 9 of the bill pocket on the opposite side wall of the case.

In Figs. 9 and 10 of the drawings, I have shown the application and use of the above method in connection with a more or less conventional type of billfold, in which the article is provided with inner and outer walls se- 70 cured together along one of their longitudinal edges and opposite end edges to form a single bill receiving pocket. In the instance illustrated, these walls are adapted to be folded along spaced lines indicated at 20 ex- 75 tending at right angles to the length of the bill receiving pocket. The inner fabric wall has the reenforcing sheet indicated at 21 ad- 80 hesively secured to one side thereof, and in the illustrated instance, this sheet is of paper. At the points adjacent the fold lines 20, said paper sheet is perforated along the parallel lines 22 and one edge of said sheet between these lines of perforations is provided with the projections 23. Thus, after the reenforc- 85 ing sheet has been applied, these projecting edge portions 23 may be readily grasped, and the parts of the reenforcing sheet between the lines of perforations 22 readily torn out. These reenforcing sheets can be readily 90 stamped out and provided with various other means, indicative of the particular portions thereof which are to be removed after the re- 95 enforcing sheet and the fabric sheet have been adhesively secured together. As shown in Fig. 11, the unreenforced part of the fabric wall of the billfold extending along the fold lines 20 may thus readily flex without undue buckling. I have shown this inner wall of the billfold provided with card receiving 100 pockets as indicated at 24, and to the unreen- 105 forced portions of the inner fabric wall of the billfold, the leather sections 25 are adapt- 110 ed to be centrally secured by the line of stitching indicated at 26. The oppositely 115 projecting portions of these leather sections have free sliding movement within the open ends of the pockets 24. However, no claim is made in this application to this particular type or construction of billfold, as it is fully 120 covered by patents heretofore granted to me.

From the foregoing description considered in connection with the accompanying drawings, it will be readily apparent that by reason of my new method of applying the reenforc- 115 ing material to the fabric sheet from which the walls of one of the bill pockets and the card receiving pockets are formed, loss of time incident to the making of proper measurements for applying the reenforcing mate- 120 rial in sections to said walls so that there will be but a single thickness of material at the hinge line or fold which flexibly connects said walls, such operation is greatly ex- 125 pedited. Therefore, billfolds, card cases and analogous articles of this kind may be very rapidly produced in large quantities and at comparatively low manufacturing cost. I have herein described and illustrated several desirable ways in which my present method 130

may be practiced, but it will be understood that the essential features of the invention may be also carried out with the use of other structural forms of the materials than those herein referred to. Accordingly, I reserve the privilege of resorting to all such legitimate changes of this nature as may be fairly embodied within the spirit and scope of the invention as claimed.

10 I claim:

1. The method of reenforcing a flexible sheet of material to provide sections thereof flexibly connected by an unreenforced portion of the material whereby said sections may be relatively moved and folded into contact with each other, which consists in applying a sheet of reenforcing material to one side of the sheet of flexible material and securing said sheets together throughout their contacting faces, and thereafter removing a part of the reenforcing sheet to permit of the relatively free flexing of such unreenforced portion of the flexible material extending between and connecting the reenforced parts of said material.

2. The method of reenforcing a flexible sheet of material to provide sections thereof flexibly connected by an unreenforced portion of the material whereby said sections may be relatively moved and folded into contact with each other, which consists in adhesively securing a sheet of flexible reenforcing material to one side of the flexible sheet of material over the entire area of the latter, and then removing relatively narrow strips of the reenforcing material extending along parallel lines at opposite side edges of the flexible sheet of material and at an intermediate point thereof to thereby provide unreenforced edge portions of the sheet of material adapted to be turned over on the adjacent edges of the remaining portions of the reenforcing sheets and to also provide an unreenforced portion of the flexible sheet of material between said reenforced portions thereof capable of a relatively free folding or flexing action in the movement of the reenforced sections of said flexible sheet of material relative to each other.

3. The method of reenforcing a flexible sheet of material to provide sections thereof connected by an unreenforced portion of the material whereby said sections may be relatively moved and folded into contact with each other which consists in perforating a sheet of reenforcing material along spaced parallel lines and securing said sheets together in superimposed relation throughout their contacting faces, and thereafter tearing out and removing the part of the reenforcing sheet between said spaced lines of perforations to permit of the relatively free flexing of such unreenforced portion of the first named sheet of flexible material extending

between and connecting the reenforced parts of said material.

In testimony that I claim the foregoing as my invention, I have signed my name hereto.

CHARLES L'ENFANT.
